ATTORNEY

UNITED STATES PATENT OFFICE.

CHARLES H. MORGAN, OF HILLSIDE, NEW JERSEY.

DISPLAY-FIXTURE.

1,303,361.

Specification of Letters Patent. Patented May 13, 1919.

Application filed November 14, 1917. Serial No. 201,894.

To all whom it may concern:

Be it known that I, CHARLES H. MORGAN, a citizen of the United States, residing at Hillside, in the county of Union and State 5 of New Jersey, have invented certain new and useful Improvements in Display-Fixtures, of which the following, taken in connection with the accompanying sheets of drawings, is a full, clear, and concise description thereof.

The present invention relates to display racks or cabinets for window shades or curtains, and has for its principal object the provision of a device of this character which 15 is especially adaptable to the requirements of department stores and the like, where it is desired to display the window shades or curtains in a manner whereby the same effect will be obtained as when the curtains 20 or shades are in actual use.

A further object of the present invention is to provide a portable display rack or cabinet of the character and for the purposes aforesaid, which may be of the sectional 25 type and may be made of wood or metal and produced at a minimum of cost.

My invention also comprehends a display cabinet or device, as hereinbefore stated, wherein means are provided to guide the 30 movement of the shades or curtains and to protect the edges thereof against injury, thereby making it possible to use the sample curtains or shades mounted therein for a much longer period of time than is now 35 possible in those cases where the edges of the shades or curtains are exposed and are subjected to handling when on exhibition or display.

Other objects and advantages of my invention will become manifest as the description proceeds, and I would have it understood that I do not limit myself to the precise details of structure or to the uses herein pointed out, but reserve unto myself all 40 equivalents thereof to which I may be entitled under my invention in its broadest aspect.

I shall now proceed to describe my invention with reference to the accompanying 50 drawings, wherein I have elected to show a preferred embodiment thereof in order to afford a clear and comprehensive understanding of the construction and operation of my invention.

55 In the drawings—

Figure 1 is a view in perspective of a dis-

play fixture or cabinet made in accordance with my invention.

Fig. 2 is a front elevation of one of the sections shown in Fig. 1. 60

Fig. 3 is a sectional elevation on the line A—A of Fig. 2; and

Fig. 4 is a transverse section on the line B—B of Fig. 2.

Referring now to the drawings in detail 65 in which like reference characters are employed to designate similar parts throughout the several views, 7 represents the sides of one unit or section of my improved form of display rack or cabinet which are united 70 by the top and base members 8 and 9 respectively, secured or fastened thereto in any suitable manner, a back member being provided as indicated at 10. Positioned within the cabinet or rack upon the inner face of 75 each side member thereof is a rectangular piece of wood or metal 11 which is slotted or grooved, as shown at 12, to provide guideways for the rollers 13 carried by the projecting ends of the curtain sticks 14. It 80 is obvious that if desired the side members on the cabinet may be made of a sufficient thickness to have the guideways formed therein or that the guideways may be provided by means of a plurality of strips of 85 material disposed parallel to each other.

The roller end of the curtain 15 is mounted in the usual holders 16 secured to the respective members 11 adjacent to the top of the cabinet or rack, as clearly shown 90 in Fig. 2.

Positioned medially of the sides of the cabinet or rack and fastened to the inner face of the top member 8 is a pulley or roller 17 operating on an axis parallel to the side 95 member 7. Similarly positioned on the base 9 is a second roller or pulley 18 operating or rotating on an axis at right angles to that of the pulley or roller 17. Fastened to the lower edge or end of the curtain 15 by any 100 suitable means, such as an eyelet 19 or the like, is a cord 20 which extends down and over the roller or pulley 18 and up behind the curtain or shade 15 through the pulley or roller 17 and parallel to the top member 105 8 of the cabinet to the pulley or roller 21 which is mounted on the outer surface of one of the side members 7 of the cabinet or fixture, as clearly shown in the drawings, the portion of the side member adjacent to 110 the pulley being slotted or cutaway to provide a suitable opening for the cord to pass

through. This pulley or roller 21 rotates on an axis parallel to that of the pulley or roller 17 and the end of the cord 20 which is disposed exterior of the cabinet or fixture may 5 be provided with a knob or the like 22 to form a grip for the person exhibiting the shades or curtains 15.

The shades or curtains 15 are of the usual spring roller type and it is obvious that by 10 grasping the gripping member 22 and pulling the cord 20 in a downward direction the shade or curtain 15 may be likewise drawn down to any desired distance within its limit of movement. To return the shade or curtain 15 to its normal or raised position, all that is necessary is to manipulate the cord 20 by means of the grip 22 in the usual manner to release the locking means within the roller 15^a, so that the shade will be rolled 20 or drawn up under the impulse of the spring in the usual manner.

The rollers 18, as heretofore described, may be fastened to the base 9 of the cabinet or fixture or they may be mounted upon a 25 transverse member 9^a fastened to the front and back portions, as shown in Figs. 1 and 3. The front member may be of the general design shown in Fig. 1 or may take any other form having a pleasing and decorative 30 effect which will add to the attractiveness of the exhibition of the curtains or shades. A dependent curtain or drapery of short length is indicated at 24, being provided adjacent to the top of the cabinet so that the 35 shade or curtain roller and the other parts positioned at the top of the cabinet or rack may not be observed by those before whom the samples are being exhibited. A curtain or drapery 23 may be mounted on a rod located adjacent to the top of the device in 40 such a manner that it may be drawn across the opening of the cabinet or fixture to protect the sample curtains 15 when not on exhibition.

45 With my invention it is obvious that any number of curtains may be disposed one behind the other and simultaneously displayed by drawing them down to varying distances, as shown in Fig. 1. Where curtains or 50 shades of different colors are used and it is desired to make selections for exhibition purposes, the cords 20 connected to the curtains are of the same color as the respective shades or curtains which enables the exhibitor to show or display any desired shade or curtain without taking a position in front of the cabinet. This is accomplished by simply grasping the exposed end of the cord 55 which is of the desired color and drawing it 60 down in the manner previously explained.

As will be apparent from the description

of my invention the cabinet or display fixture may be made as a single or independent unit or a complete fixture may be composed of two or more units such, for instance, as 65 shown in Fig. 1. The cabinet or fixture may also be mounted on rollers or casters, if desired, so that it may be moved from place to place to suit the convenience of the exhibitor.

70 Other modifications of my invention may be made all of which I would have it understood I consider within the spirit and scope of my invention as set forth in the appended claims.

75 Having thus described my invention what I claim as new and desire to secure by Letters Patent of the United States, is:

1. A display fixture for flexible articles, as window shades and the like, comprising 80 a cabinet, spring rollers on which the articles to be displayed are mounted, secured to the interior of the cabinet and near the top thereof, and so disposed that a plurality of articles may be displayed simultaneously 85 without altering the position of the rollers relatively to the cabinet, a cord secured to the bottom of each article for actuating the same to extended or display position, rollers at the bottom and top of the cabinet, the 90 cords passing from their point of attachment to the articles downwardly around the first-named rollers and upwardly about the second named rollers and from thence substantially at a right angle out through the 95 side of the cabinet, and guides engaging the lower outside edges of the articles, the cords at all times and the articles when on display maintaining themselves in extended position.

100 2. A display fixture for flexible articles, as window shades and the like, comprising a cabinet, spring rollers on which the articles to be displayed are mounted, supports for the rollers rigidly secured to the cabinet 105 adjacent the interior of the top thereof, so disposed that the articles to be displayed will be arranged parallel to each other, a cord secured to the bottom of each article for actuating the same downwardly, rollers 110 at the bottom and top of the cabinet, said cords extending from the bottom of the articles downwardly around the rollers at the bottom of the cabinet and upwardly about the rollers at the top of the cabinet and from 115 thence out through the side of the cabinet near the top thereof, and guides for directing the movements of the articles, the articles when on display and the cords for actuating them maintaining themselves in extended position.

CHARLES H. MORGAN.
